FOLDING DISPLAY CABINET

Joseph P. Spang, Quincy, Mass.

Application November 28, 1933, Serial No. 700,055

2 Claims. (Cl. 312—114)

This invention relates to display cabinets or counters such as are used in stores for displaying goods offered for sale, and one of the objects of the invention is to provide an improved display cabinet which is constructed so that when it is not in use it can be folded into a compact bundle and readily stored.

Stores are frequently desirous of making a special display of some merchandise offered for sale and if the store is one having a limited counter space the use of any part of such limited counter space for the desired display is apt to hamper regular merchandising operations of the store.

My improved folding display stand admirably meets such a situation because it provides extra counter space which can be readily set up in any store and used for the special display thereby leaving the entire normal counter space available for regular merchandising operations. When the occasion for the display has terminated the folding display cabinet can be folded up and stored in a relatively small space ready for some future occasion.

In order to give an understanding of the invention I have illustrated in the drawings some selected embodiments thereof which will now be described after which the novel features will be pointed out in the appended claims.

In the drawings, Fig. 1 is a perspective view of a display cabinet embodying my invention;

Fig. 2 is an enlarged sectional view on the line 2—2, Fig. 1;

Fig. 3 is a fragmentary detail illustrating the construction at one corner of the glass front, the glass being omitted;

Fig. 4 is a section on the line 4—4, Fig. 3 showing the glass in position;

Fig. 5 is a section on the line 5—5, Fig. 2 with parts broken out, the full lines showing the sides folded and the dotted lines showing the sides in their operative position;

Fig. 6 is a section on the line 6—6, Fig. 2;

Fig. 7 is a front view of the display cabinet, the dotted lines showing the folded position of the sides;

Fig. 8 is a top plan view;

Fig. 9 is a perspective view showing the back side and one end of a display stand having a different construction from that shown in Figs. 1 to 8;

Fig. 10 is an enlarged fragmentary sectional view on the line 10—10, Fig. 9;

Fig. 11 is an enlarged sectional view on the line 11—11, Fig. 10;

Fig. 12 is a fragmentary sectional view on the line 12—12, Fig. 9 with parts broken out.

The display cabinet shown in Figs. 1 to 8 is indicated generally at 1 and may be made of any suitable material but preferably of metal. It comprises a back section 2, two side sections 3, 4 which are hinged to the back section and adapted to fold thereagainst and a plurality of shelves also hinged to the back section and adapted, when the display stand is folded, to be swung downwardly against the back. The shelves are designated 5, 5a, 5b and 5c.

The back section 2 comprises the two angle iron posts 6 which are connected by means of tie rods 7 and also by means of a back sheet 30. The tie rods 7 are shown as having reduced ends 8 that extend through side legs 9 of the posts 6, said rods being clamped to said legs by means of nuts 10.

The side sections 3 and 4 are hinged to the front edges of the legs 9 of the angle iron 6 and are adapted to fold backwardly against the back section. These side sections may conveniently be formed of sheet metal 11 although any other material may be used. Each side section has an angle iron member 12 at its front edge, said angle iron members forming the front legs or posts of the display cabinet. The sheet metal members 11 are secured to the rearwardly-extending legs 13 of the angle irons 12 in any suitable way, as by means of screws or by welding.

Any suitable form of hinge connection between the side members 3, 4 and the rear posts 6 may be employed. As herein shown said side members are hingedly connected to the post 6 through the medium of hinges 14, one leaf of each hinge being secured to the leg 9 of a post 6 and the other leaf of each hinge being secured to a reinforcing strip 15 which in turn is secured to the inner side of the side sheet 11 at the rear edge.

The upper end 17 of the front posts 12 are bent rearwardly so that the upper part of the display cabinet has an inclined front.

The shelves may conveniently be made of sheet metal. The shelves 5a, 5b, 5c are shown as hinged to tie rods 7 and for this purpose the rear edge 45 of each shelf is bent to form the loop portion 18 which encircles the tie rod. These shelves are thus free to swing from their operative horizontal position shown in full lines Fig. 2 into their folded position shown in dotted lines Fig. 2. The spacing between each shelf and the shelf above is preferably greater than the width of the shelf so that when the shelves are in the folded position shown in dotted lines Fig. 2 they will lie in the same plane.

The upper shelf 5 is hinged to a cross bar 31 of angle iron which extends from one post 6 to the other at the upper end thereof, the hinge connection for such shelf 5 being indicated generally at 5 32.

The side members 3 and 4 are provided with shelf-supporting rails 19 by which the shelves are supported in their operative position. These rails are secured to the side sheets 11 of the side members and the upper portion 20 of each rail is offset inwardly thereby to provide a groove 21 between it and the sheet 11 as best seen in Fig. 6. The side edge of each shelf is formed with a down-turned lip 22 adapted to be received in the groove 15 21. The shelves rest at the top edge of the offset portion 20 of the rails and the engagement of the lips 22 in the groove 21 serves to lock the shelves and side members securely together. The shelves 5 and 5a are of less depth than the other shelves 20 because of the inclined position of the upper part 17 of the posts 12.

I may, if desired, provide the glass front for the shelves 5a, 5b and such a construction is illustrated in the drawings. The glass front is indicated at 23 and it has a sufficient transverse dimension so that the edges of the glass front rest on the inclined portion 17 of the front posts, said glass preferably extending the full vertical dimension of said inclined portion 17.

30 The glass is supported in a suitable metal frame comprising the bottom and top rails 33, and 35 and the side rails 34, 36. The top and bottom rails 35, 33 and the end or side rails 34 are rigidly connected on the end rail 36, which is separable 35 from the other rails. This construction permits the glass with its attached rail 36 to be withdrawn from the top and bottom rails in case it is necessary to remove the glass. The top rail 35 is hinged to the front edge of the top shelf 5 as indicated at 38 and hence the glass is supported partially by said top shelf and partially by the inclined portion 17 of the front rails.

45 The end rail 36 is detachably secured to the top and bottom rails 35, 33 by means of the construction shown in Figs. 3 and 4. The ends 39 of the side rails 36 are widened sufficiently to receive the ends of the top and bottom rails 35, 33 and said side rail 36 is secured to the other rails by means of screws 40 which screw through the overlapping portions of the rails.

50 The top rail 35 and the bottom rail 33 each has a filling block 41 at the end thereof which is set within the side rail 36, said filling blocks furnishing ample anchorage for the threads of the screws 40. When the screws 40 are removed then the glass with the end rail 36 can be readily withdrawn from the top and bottom rails.

55 The glass front 23 is provided at its lower end with a handle 43 by which said front may be raised in order to give access to the shelves 5a and 5b. When the cabinet is to be folded the shelves are lifted from engagement with the supporting rails 19 and the sides are then swung outwardly slightly to permit the shelves to fold into the dotted line position Fig. 2. The top shelf 5 with its attached glass front 23 may then be folded against the folded shelves 5a, 5b, 5c and for this purpose the hinge connection 32 for the top shelf 5 is set sufficiently in front of the tie rods 7 so as to permit said shelf 5 and attached glass to take a folded position in front of the folded shelves as shown by dotted lines Fig. 2 and full lines Fig. 5. When the shelves and the front have thus been folded then the sides may be folded 70 inwardly as shown by full lines in Fig. 5.

The hinge connections 14 for the sides are located sufficiently far from the back so that the sides 3 and 4 can be folded over against the folded shelves and front. The device when folded occupies a very small compact space. 5

The construction is such that the cabinet can be readily erected. This involves simply swinging the sides from their folded position into a position at substantial right angles to the back and then swinging the shelves upwardly and engaging the lips 22 on the edges of the shelves with the supporting rails 19. When this has been accomplished the shelves serve to tie the sides firmly together and hold them in a position to support the glass front 23. The structure can 15 then be used for the display apparatus.

Because of the folding nature of the device it can be readily used as an emergency display cabinet for exhibiting a display in a store or in any desirable location and when it has served 20 its purpose it can be folded and stored in a small space. The device is of special utility in stores that have a somewhat limited counter space because it provides additional counter space which can be brought into use whenever desired and 25 can be stored in a small space when not needed.

In Figs. 9 to 12 I have illustrated another embodiment of the invention in which the side sections are of glass or some transparent material and in which the back is made with doors that 30 can be opened to give access to the upper shelves. The display cabinet illustrated in these figures is indicated generally at 44 and it comprises the back section, side sections and front sections as in the other embodiment of the invention. Said 35 display cabinet also comprises the two angle iron posts 6 as illustrated in Figs. 1 to 8 which are connected by tie rods 7 on which the shelves 5a, 5b are hung and the upper angle iron cross bar 31 to which the top shelf 5 is hinged as shown 40 at 32. The side members are also hinged to the posts 6 and each side member has at its front edge the angle iron front post 12, the upper end 17 of which is bent backwardly slightly. The front of the cabinet is also closed by a glass panel 45 23 which rests against the inclined portion 17 of the front post, the upper edge of which is hinged to the front edge of the top shelf 5 as shown at 38.

The construction thus far described is similar to that shown in Figs. 1 to 8. In the display 50 cabinet 44, however, the back is closed by two sliding doors 45, 46 which are preferably made of sheet metal and each of which is slidably supported at its upper end on a rod 47 that extends between and is supported by the rear posts 6. 55 The upper edge of each shelf is shown as formed into a loop 48 which encircles the corresponding supporting rod 47. The bottom edges of the two doors are received in a channel iron guide member 49 which extends between and is secured to the posts 6. Each door is provided with a finger opening 50 into which a person may insert his finger in order to slide the door open. Each door has a transverse dimension equal to slightly more than half the transverse dimension of the cabinet 65 net so that the adjacent edges of the doors overlap slightly. Either door can be slid on its guides 47, 49 into open position and by this means the contents of the shelves 5a and 5b are readily accessible from the back. 70

The end or side sections of the display cabinet 44 are of glass so that the contents of the shelves can be readily seen through said sides. Each side section comprises a vertical strip 51 which is hinged to the front edge of the corresponding 75

posts 6 by suitable hinges 52 and these strips 51 are connected with the front post 12 through cross rails 53, 54, 56 which are constructed so that they function both as means for supporting 5 glass panels 55 and for supporting the shelves in their operative position.

The upper cross bar 56 is formed with a groove 57 to receive the down-turned lip 21 on the edge of the top shelf 5 and is also provided on its under 10 side with a groove 58 to receive the upper edge of the upper glass panel 55. Each of the two transverse bars 54 is formed on its upper edge with a groove 59 designed to receive the lower edge of the glass panel 55 above it and said groove is 15 also wide enough to receive the down-turned edge 21 of the shelves 5a, 5b in addition to the glass panel as shown in Fig. 12. The lower edge of each of the cross rails 54 is provided with a groove 60 to receive the upper edge of the glass 20 panel beneath it. The bottom cross rail 53 is channel shaped and receives the lower edge of the bottom glass panel 55 and the down-turned lip of the bottom shelf. This is clearly shown in Fig. 12.

25 61 indicates packing which may be inserted between the lower edge of each glass panel and one wall of the channel in which it is received, such packing serving to hold the glass tight when the shelves have been disconnected from the 30 cross pieces and folded in their vertical position.

The manner in which the construction shown in Figs. 9 to 12 is used is similar to that described with reference to the device shown in Figs. 1 to 8 except that the cabinet 44 can also be conveniently 35 used as a cabinet from which sales are to be made because of the easy access afforded to the shelves from the rear by means of the sliding doors 45, 46. The cabinet 44 is also capable of being folded into a small space for when the

shelves are raised to disconnect the lips 21 on the ends thereof from the cross bars 53, 54, 56 then said shelves may be dropped in their vertical folded position against the back and the top shelf with the glass front may also be folded into a vertical position in front of the folded shelves. When this has been done then the side or end sections can be folded against the folded front as shown at the right in Fig. 11.

I claim:

1. A folding display cabinet comprising a back section, including two angle iron posts, tie rods connecting said posts, shelves hinged to the tie rods and adapted to swing downwardly against the back section, side sections hinged to the front 10 edges of the forwardly extending legs of the posts and adapted to fold backwardly against the folded shelves, and a front closure member hinged to its upper edge to the front edge of the top shelf and adapted to rest against the front edges 15 of the side sections when the top shelf is in operative position.

2. A folding display cabinet comprising a back section, a plurality of shelves pivoted to the back section and adapted to fold downwardly thereagainst, two side sections pivoted to the back section and adapted to fold backwardly against the folded shelves, said side sections having means to support the shelves when the latter are in operative position, and a closure member hinged to the front edge of the top shelf and adapted to rest against the front edges of the side sections when said top shelf is in operative position, and to rest against the folded shelves when the top shelf is folded, the combined vertical dimension 30 of the top shelf and the front closure when in folded position being less than the vertical dimension of the back section. 35

JOSEPH P. SPANG.
